UNITED STATES PATENT OFFICE.

FRANK J. SEDER, OF CLEVELAND, OHIO.

INK-FEEDING ATTACHMENT FOR PRINTING-PRESSES.

SPECIFICATION forming part of Letters Patent No. 424,029, dated March 25, 1890.

Application filed November 16, 1889. Serial No. 330,580. (No model.)

To all whom it may concern:

Be it known that I, FRANK J. SEDER, a citizen of the United States, residing at Cleveland, in the county of Cuyahoga and State of Ohio, have invented certain new and useful Improvements in Ink-Feeding Attachments for Printing-Presses, of which the following is a full, clear, and exact description, reference being had to the accompanying drawings.

10 In most printing-presses, and especially in cylinder-presses, the fountain-roller journaled in the ink-fountain is caused to revolve slowly in one side thereof and by its revolution to take up a quantity of the ink with which it is in contact. Other rollers by contact with said roller take off this ink, distribute it evenly, and deliver it to the form-rollers. When a thin ink is used, it will generally fall by gravity down the sloping bottom of the fountain, and thus always remain in contact with the fountain-roller; but when a stiff ink is used it will not run, and the roller, after a few revolutions, will be no longer in contact with it. It is therefore necessary for the pressman to frequently push the ink against the roller, and thereby secure the proper ink-supply upon the form-rollers. This requires a constant watchfulness on the pressman's part and a frequent stopping of the press, or at least a cessation of the printing process.

The object of my invention is to provide an attachment for a printing-press by which the ink is automatically pushed toward the fountain-roller and kept in contact therewith until so much of the ink as the attachment is adapted to move into contact therewith is substantially exhausted.

To this end my invention consists, primarily, of a knife arranged in the fountain, combined with mechanism for moving said knife toward and from the fountain-roller at frequent intervals.

It also consists in the combination and arrangements of parts, and in the details of construction hereinafter described, and pointed out definitely in the claims.

The drawings represent an embodiment of my invention applicable particularly to what is known as the "Cranston" cylinder-press.

In the drawings, Figure 1 represents a side

elevation of the ink-fountain having my improvement applied thereto. Fig. 2 is a transverse sectional view of the same. Fig. 3 is a top plan view. Fig. 4 is a detached view of the reciprocating knife and the frame to which it is attached; and Fig. 5 is a transverse sectional view of a part of said frame, showing the particular means I prefer for attaching the knife to the frame.

Referring to the parts by letter, A represents the ink-fountain, in the lower side of which is journaled the fountain-roller B. In the bottom of this fountain is generally placed an adjustable feed-knife C, or, as it is sometimes called, an "ink-doctor." The ink is placed upon this feed-knife in contact with the roller. Upon the end of the roller is generally placed a ratchet-wheel b, and a pawl D, pivoted to a reciprocating lever d, causes said roller to revolve step by step. Besides sustaining the ink, the feed-knife C also regulates by its position the amount of ink which the roller shall carry away. In order that this ink shall be pushed down automatically into contact with the roller, I provide a feeding-knife E, the lower edge of which rests upon the feed-knife C. This knife is connected to the front bar of a suitable frame F, which is moved back and forth by the oscillation of the rock-shaft G. This rock-shaft is journaled in brackets H, which in the frame shown are secured to the ink-fountain. Upon each end of the rock-shaft is secured a crank-arm g, and to the outer ends of these crank-arms the frame F is pivotally connected. The particular means shown for oscillating this rock-shaft consist in a depending crank-arm I, attached to the rock-shaft, which crank-arm is connected by the link J to the same lever d which operates the pawl D. The crank-arm I is provided with a slot through which passes the pivot-pin by which the link J is attached thereto. By moving the pivot-pin up and down this slot and then securing it the throw of the knife is adjusted as circumstances may require.

With the mechanism above described it will be noticed that when the lever d is moved to cause the fountain-roller to revolve it also causes an oscillation of the rock-shaft, by which the knife E is moved toward the fount-

ain-roller, thereby pushing the ink before it. The lower edge of this knife slides back and forth upon the feed-knife C, and in its backward movement will slide over any obstacle thereon. The ink adheres to the knife, and as said knife moves backward and forward the ink is "worked"—that is to say, its particles are kept in motion—which serves to keep the ink in a plastic condition, and at each forward movement of the knife the ink is pushed toward the feed-roll and into contact therewith. Without some such attachment as this the ink in the fountain becomes stiff, and after a few revolutions of the roll 15 is no longer in contact therewith.

By the use of the above-described attachment a very considerable quantity of the ink in a fountain may be used without attention from the pressman. When the knife no longer moves the ink into contact with the roller, the throw of said knife is adjusted anew, as above pointed out.

When a narrow form is being printed upon the press, it is customary to use only a part 25 of the ink-fountain.

In order that my attachment may be used with a printing-press at such times, I make the feeding-knives E in sections, which I secure by means of set-screws in a slot in the 30 front bar of the frame. Thus if only a part of the fountain is being used and partitions are placed therein to prevent the spreading of the ink beyond the required limits I attach to the front bar of my oscillating frame 35 a knife or several knife-sections of sufficient width to operate easily between the partitions in the fountain.

The above-described embodiment of my invention is the best form now known to me for 40 use with the Cranston press; but the invention may readily be adapted to use with other presses, and generally with no change except

in the particular mechanism for operating the rock-shaft.

Having thus described my invention, what I 45 claim as new, and desire to secure by Letters Patent, is—

1. In a printing-press, in combination, an ink-fountain, a fountain-roller, a knife, and mechanism for sliding said knife in said fountain toward and from the roller, substantially as and for the purpose specified.

2. In a printing-press, in combination, an ink-fountain, a fountain-roller, a rock-shaft and means for oscillating the same, a frame 55 operated thereby, and a knife secured to said frame and adapted to move back and forth within the ink-fountain toward and from the roller, substantially as and for the purpose specified.

3. In a printing-press, in combination, an ink-fountain and a fountain-roller, a reciprocating lever adapted to revolve said roller automatically, a rock-shaft having crank-arms attached thereto, a frame pivotally connected 65 with said crank-arms, a knife attached to said frame, a slotted crank-arm attached to said rock-shaft, and a link connecting said crank-arm with the said lever, substantially as and for the purpose specified.

4. In a printing-press, in combination, an ink-fountain, a fountain-roller, an oscillating lever adapted to revolve said roller intermittently, a rock-shaft, crank-arms attached thereto, suitable connections between said lever and rock-shaft whereby the same is oscillated, a frame attached to said crank-arms, and a sectional knife removably secured to the front end of said frame, substantially as and for the purpose specified.

70 FRANK J. SEDER.
